UNITED STATES PATENT OFFICE.

CLAUDIUS C. KING, CHARLES B. LAMBERT, AND JOSEPH H. GIBBLE, OF SIOUX CITY,
IOWA.

SHIRT-FINISHING DEVICE FOR LAUNDRIES.

1,158,234.

Specification of Letters Patent.

Patented Oct. 26, 1915.

Application filed July 22, 1915. Serial No. 41,373.

To all whom it may concern:

Be it known that we, CLAUDIUS C. KING, CHARLES B. LAMBERT, and JOSEPH H. GIBBLE, citizens of the United States, and residents of Sioux City, in the county of Woodbury and State of Iowa; have invented certain new and useful Improvements in Shirt-Finishing Devices for Laundries, of which the following is a specification.

10 The present invention relates to laundry machines.

In commercial laundries the usual method of finishing the various parts of shirts consists in pressing or ironing the neck-bands, 15 cuffs, bosoms, sleeves, etc., by machines designed to press or iron the respective parts. These machines, however, fail to perform the work perfectly, and it is necessary, finally, to iron the unfinished portions by 20 hand ironing. This hand finishing requires that the operator hold the shirt upon the board with one hand while the other hand operates the iron. In view of the vast number of garments which are laundried, this 25 hand finishing is an expensive item, and requires great care on the part of the operator to preserve the proper shape of the garment.

The present invention, has, therefore, for 30 its primary object, the production of an improved device for holding shirts while being hand finished.

Another object of the invention is the production of a device of this class particularly 35 adapted to preserve the shape of shirts while being hand finished.

A further object of the invention is the production of an improved device of this class adapted to automatically adjust itself 40 to all sizes of shirts.

A still further object of the invention is the production of an improved article of this class embodying certain novel features of construction which reduce the cost of 45 manufacture and increase the efficiency.

With these and other objects in view, the invention consisting in the construction, combination and novel arrangement of parts, will be fully understood from the following description, reference being had to the accompanying drawings which form a part of this application and in which like characters of reference indicate correspond-

ing parts throughout the several views, of which,—

Figure 1 is a plan of an ironing-board equipped with the preferred embodiment of the invention; Fig. 2 is a front elevation of the same, the foot-lever links being cut away. Fig. 3 is a side elevation of the same, parts being cut away; and Fig. 4 is an enlarged elevation, partly in section, of one of the toggle members.

Although we have illustrated and herein-after described an embodiment suitable for practising the invention, we would not be understood as being limited to the specific structure chosen for illustration, for various alterations in the details of construction and arrangement of parts may be made without departing from the spirit and scope of the invention, as defined in the appended claims.

The invention contemplates, broadly, mechanism including an expanding band to engage the interior of the neck-band of a shirt and adapted to be held retractably upon the ironing-board, retractable members for holding the shoulders of the shirt upon the ironing-board, and means for controlling the expanding band and said members.

In its preferred form the invention embodies means controlled by the operator for retracting the band and said members, and while in retracted position to contract the band to permit the removal and application of the neck-bands from and to said band.

Referring now to the illustrations, 5, is a horizontal shaft, the intermediate portion 90 of which is preferably square, or flat-sided, and the end portions of which are cylindrical, as at 6, and journaled in suitable bearings, 7, mounted upon the ironing-board, 8, and adjacent the front edge 95 thereof.

Upon the ends of the squared portion of the shaft are mounted rearwardly-disposed arms, 9, the ends of which are bent downwardly and provided with feet, 10, of rubber or other yieldable material, to engage the shoulders of a shirt, as presented in Fig. 1. The arms are slidably mounted upon the shaft to permit of their adjustment toward or from each other to suit 105 various sizes of shirts.

Upon the center portion of the shaft are slidably mounted companion arms, 11, the ends of which are bent downwardly, and are secured, respectively, to the inner sides of opposite segments of a band, 12, each segment of which is free from the other.

Upon the shaft and intermediate the latter arms is secured a forwardly-disposed arm, 13, between which and the adjacent 10 arms are interposed compression-springs, 14, which tend to force the latter arms from each other and thereby expand the band by forcing the segments from each other.

The end portions of the shaft are encircled by retracting-springs, 15, each having one end secured to the shaft and the other to the adjacent bearing. The said springs serve to hold the arms 9 and band 12 in 15 yieldable engagement with the ironing-board.

The arms 11 are interconnected by toggle-jointed links, 16, the ends of which are universally pivoted to the said arms, as by providing sockets, 17, (Fig. 4) on the under 20 sides of the arms to inclose balls, 18, on the ends of rods 19, threaded into the toggle members.

To the nodal point of the toggle links is secured one end of a flexible link, 20, the 25 opposite end of which is secured to a foot-lever, 21, fulcrumed upon a suitable bearing, 22, mounted, (we will assume), upon the floor.

The lever, 21, and arm 13 are interconnected by a link, 23, the upper end of which is provided with a bifurcated head, 24, which incloses the end of the arm 13 and is provided with a longitudinal slot to inclose 30 a transverse pin, 25, in the arm.

On opposite sides of the foot lever, the 35 fulcrum pin is encircled by the ends portions of a spring, 26, the extreme ends of which are secured to the sides of the bearing, and the intermediate portion of which passes under and engages the foot-lever. The said spring serves to retract the lever and hold the same in its upper or normal position.

The slotted head of the link, 23, permits 40 the foot-lever to move upwardly a distance after the shirt-engaging members are seated upon the ironing-board, to slacken the flexible link and relieve the toggle members of all strain.

In operating the device the foot-lever is first depressed, to coat with the link, 23 to 45 turn the shaft and raise the shirt-engaging members; and to, coat with the link, 20, and toggle members to contract the band.

The operator then holds the lever down thus 50 holding the shirt-engaging members in the elevated position indicated in dotted lines in Fig. 3. While the members are held in this position, a shirt is applied by placing 55 the neck-band, which has been previously

buttoned, around the contractible band and then slowly releasing the foot-lever, whereupon the band expands into engagement with the neck-band. After the neck-band has been thus engaged and supported and prior to the return of the shirt-engaging members, to the ironing-board, the operator spreads the shirt upon the ironing-board. The lever is then completely released and the shoulder portions of the shirt are impinged by the arms, 9. The shirt having been completed, the foot-lever is again depressed to permit the removal of the completed shirt and the application of another. It is now evident that the shirts are readily 60 applied and removed, and held securely in position upon the board for hand finishing.

Having thus described our invention, what we claim as new and desire to secure by Letters Patent of the United States, is,—

1. A device for holding shirts upon an ironing board comprising, a contractible element adapted to engage the interior of the neck-band of a shirt and movable toward and from the ironing-board, members 90 movable toward and from the ironing-board and adapted to impinge the upper portions of the shirt, and means for moving said element and members and contracting said element.

2. A device for holding shirts upon an ironing board comprising a contractible element adapted to engage the interior of the neck-band of a shirt and held in yieldable engagement with the ironing-board, members 100 adapted to impinge the upper portions of the shirt and held in yieldable engagement with the ironing-board, and means for raising said element and members and contracting said element.

3. A device for holding shirts upon an ironing-board comprising a rock-shaft mounted upon the ironing-board, an expandable and contractible band carried thereby and adapted to engage the interior of the neck-band of a shirt, arms carried by the rock-shaft to impinge the shoulder portions of the shirt, means for actuating the rock-shaft to raise and lower the band and said members, and mechanism controlled by said 110 means for expanding and contracting said band.

4. A device for holding shirts upon an ironing-board comprising a rock-shaft mounted upon the ironing-board, an expandable and contractible band carried thereby and adapted to engage the interior of the neck-band of a shirt, arms carried by the rock-shaft to impinge the shoulder portions of the shirt, and adjustable toward and 120 from each other, means for actuating the rock-shaft to raise and lower the band and said members, and mechanism controlled by said means for expanding and contracting 125 said band.

5. A device for holding shirts upon an ironing-board comprising a suitable support, a horizontal shaft mounted rotatably thereon, companion arms slidably carried by the shaft and yieldable toward each other, an open band adapted to be inclosed by the neck-band of a shirt and embodying two segments each separated from the other, said segments being secured, respectively, to 25 said arms, arms carried by the shaft to engage the shoulder portions of the shirt, means for turning the shaft to raise said arms and move said first arms toward each other, including a lever, a lateral arm upon 30 the shaft and connected with the lever, toggle-links pivotally connected with said first arms, and a link between said lever and toggle-links, and means for retracting the shaft.
6. A device for holding shirts upon an ironing-board comprising a suitable support, a horizontal shaft mounted rotatably thereon, companion arms slidably carried

In testimony whereof we have hereunto set our hands.
